UNITED STATES PATENT OFFICE.

JAMES AUSTIN PAGE, OF PHILADELPHIA, PENNSYLVANIA, ASSIGNOR TO
THE ABRAM COX STOVE COMPANY, OF SAME PLACE.

DESIGN FOR AN ORNAMENTAL FIRE-PLACE LINING.

SPECIFICATION forming part of Design No. 16,132, dated June 16, 1885.

Application filed May 15, 1885. Term of patent 23 years.

To all whom it may concern:

Be it known that I, JAMES AUSTIN PAGE, a citizen of the United States, residing at Philadelphia, in the county of Philadelphia and State of Pennsylvania, have invented and produced a new and original Design for an Ornamental Fire-Place Lining, of which the following is a specification, reference being had to the accompanying photograph, forming a part thereof.

The photograph (marked A) gives a clear perspective view, and shows completely the full character of my new design.

It consists of a small rosette, with a square pyramidal center repeated eighty times in horizontal lines, eight in a row, upon the back, and the same rosette repeated fifty times in horizontal lines, five in a row, upon each of the side jambs, excepting the space required and occupied by a sculptured front face-like-

ness upon the back about one-third down from the top. This is a face-likeness of an old Greek, indicating age and placidity, with brow wrinkled as by age, hair roughly strewn upon the head, beard full and heavy, eyes full, with a look of fixedness, nose Grecian, as fully shown in the photograph. 25

I claim—

The design for an ornamental fire-place lining, consisting of small rosettes having a 30 square pyramidal center and small globular ornaments interspersed in all the open squares around them, and the back having upon its central upper part the representation of an old Greek, as fully shown in the photograph.

J. AUSTIN PAGE.
